N. FULTON

SPIT CURL HAIR CURLER

Filed Feb. 24, 1926

NELL FULTON INVENTOR.

BY *Arnold F. Lange*
ATTORNEY

UNITED STATES PATENT OFFICE.

NELL FULTON, OF NEW YORK, N. Y.

SPIT-CURL HAIR CURLER.

Application filed February 24, 1926. Serial No. 90,293.

My invention relates to devices for curling locks of hair into curls of the kind which are generally known as "spit-curls" and which are characterized by their tightly 5 pressed position against the forehead or the side of the head. My invention further contemplates the provision of a hair curler for shaping the locks of hair into a variety of 10 curls other than the "spit-curls", and which is simple in construction and use.

Having in view these and other subjects which will be mentioned in the following description, I will now refer to the drawings, in which—

15 Figure 1 is an illustration of the spit-curl hair curler.

Figure 2 shows the same hair curler with the tape partially wound on the support.

Figure 3 shows the tape entirely wound 20 on the support, the end of the support being bent over to prevent the unwinding of the tape.

Figure 4 shows the hair curler with the 25 enclosed lock of hair wound in spiral form.

Figure 5 shows another form of winding the hair curler.

Figures 6, 7, and 8 illustrate the use of the spit-curl hair curler for forming various kinds of curls.

30 My spit-curl hair curler is made of two parts. The support 10 must be fairly stiff but bendable and non-resilient. Perhaps the best materials for this purpose are lead and copper, but owing to the availability of 35 the silk and cotton covered wire such as is used in electrical work, I prefer to employ such wire in making the support 10. The silk or cotton covering of the wire prevents the staining of the hair due to the oxidation 40 of the copper. The coating of the electric wire is also usually impregnated with wax or paraffin which still further protects the hair. The length of the support 10 may vary with the length of the locks of hair,

45 the preferred length being slightly greater than the length of the lock of hair to be curled. To the support 10 is secured a tape 11, the tape being somewhat longer than the support as shown in Figure 1. The tape

is secured directly to the covering of the 50 support 10 at such an angle that it may readily be wound spirally on the support.

In use, the hair curler is positioned 55 against the lock of hair with the junction of the parts 10 and 11 near the scalp. The lock of hair is held against the support 10 while the tape is wound spirally about the support and lock of hair as shown in Figure 2. When the tape reaches the end of the support, the support must be bent over 60 as shown in Figure 3 to prevent unwinding of the tape. The curler with the enclosed lock of hair may then be twisted or wound into any desired form as shown for example in Figures 4 and 5. If left over 65 night the curl becomes more or less fixed in the lock of hair and retains its form after removal of the curler in the morning.

Owing to the small size of the parts my 70 hair curler can cause no inconvenience to the user during the night. It may be easily applied to the hair at night and even more easily removed therefrom in the morning. Since the lock of hair is tightly enclosed in the hair curler it is possible to curl even 75 the shortest locks of hair. There is no danger of staining the hair, regardless of how light the shade of the hair is. While the curler possesses numerous and marked advantages over hair curlers of the present 80 types, it is possible to manufacture and sell them at a very low figure. This is due to the fact that there are only two parts, both of which are obtainable at a relatively low cost, and the only operation is the uniting 85 of these two parts by sewing or otherwise.

Having thus described my invention in such full, clear, and exact terms that its construction and utility will be readily understood by others skilled in the art to which it pertains, what I claim as new and desire to secure by Letters Patent of the United States is:

1. A hair curler comprising a non-resilient core member, and a binding tape carried by the core member for winding thereabout and over a strand of hair to secure the strand of hair lengthwise along the core 95

member, said core member adapted to be bent into any desired shape with the strand of hair secured thereto.

2. A hair curler including a length of copper wire having a fabric covering, and a flat tape secured to the fabric covering at the end thereof, said tape being secured to the fabric covering at such an angle to the

said wire that it may be wound spirally about said covered wire to completely surround said covered wire without overlapping at the edges of the tape. 10

In testimony whereof I affix my signature.

NELL FULTON.
